UNITED STATES PATENT OFFICE.

HENRY WELSCH AND MOSES R. BUCHANAN, OF EL PASO, TEXAS.

ICE-SUPPORTING PLATE.

Application filed February 17, 1922. Serial No. 537,184.

To all whom it may concern:

Be it known that we, HENRY WELSCH and MOSES R. BUCHANAN, both citizens of the United States, residing at El Paso, in the county of El Paso and State of Texas, have invented new and useful Improvements in Ice-Supporting Plates, of which the following is a specification.

This invention relates to ice supporting plates, the primary object of the invention being to provide means of a simple nature for supporting a cake of ice and holding the latter against slipping or sliding in any direction when so supported, the invention being adaptable particularly, though not exclusively, for use upon vehicles, such as the running board of an automobile.

A further object of the invention is to provide a plate of the character mentioned and for the purpose stated which may be quickly and easily applied to the running board and which requires no means other than provided by the plate for preventing the cake or block of ice slipping.

A still further object of the invention is to provide a plate of the character stated which is of extremely simple construction, which may be manufactured at low cost, which may be applied to a vehicle or other base by those other than skilled mechanics, which does not form an obstruction or otherwise interfere with the use of the running board or other part of the vehicle to which the plate is attached, which is inexpensive in manufacture, and which will prove highly practical and efficient in use.

With these and other objects in view, the invention consists of the features of construction, combination and arrangement of parts, hereinafter fully described and claimed, reference being had to the accompanying drawing, in which:—

Figure 1 is a perspective view of a portion of a conventional type of motor vehicle running board and illustrating the application thereto of an ice supporting plate constructed in accordance with the invention,

Figure 2 is an enlarged plan view of the plate,

Figure 3 is a fragmentary sectional view taken substantially upon line 3—3 of Figure 2,

Figure 4 is a similar view taken upon line 4—4 of Figure 2, and

Figure 5 is a transverse sectional view taken upon line 5—5 of Figure 2.

The invention comprehends generally the arrangement of a metallic plate secured flat upon the upper surface of the running board of a vehicle, or upon any other suitable base, and which is equipped with upstanding teeth to bite into the under surface of the ice and to prevent the body of ice slipping or sliding upon the plate. These teeth are preferably disposed at angles to each other, so that slippage of the ice in any direction will be prevented.

More specifically, the plate of our invention includes a flat metallic base 6 in the form of a thin plate, having openings 7 extending therethrough at suitable places for the reception of retaining screws, rivets, bolts, nails or the like indicated at 8, in order that the plate may be securely anchored to the running board 9. The teeth are indicated generally at 10, and include portions of metal as shown struck up from the body of the plate to constitute obstructions and to bite into the lower surface of a block of ice 11 resting upon the plate. In the present instance, the plate is provided with teeth arranged in longitudinal series thereon, and preferably these teeth are staggered laterally. The teeth of adjacent rows will be disposed at angles to each other, the teeth constituting the extreme end rows shown in Figure 2 preventing movement of the ice block laterally of the plate, while the intermediate row has its teeth disposed so as to resist sliding of the block longitudinally of the plate. If desired, the teeth may be disposed at angles other than those disclosed herein.

In forming the teeth 10 in the present instance, the thin metallic plate 6 may be subjected to a stamping process, wherein dies of substantially circular shape are brought to bear at properly spaced intervals upon the plate and to cut the metal from the plate at diametrically opposite points, these cut portions being at the same time bent out of alignment with the upper surface of the plate and caused to protrude and form the teeth 10.

In practice, the plate is applied to the running board in the manner shown, and it is apparent that a block of ice placed upon the plate will at once be engaged in its under surface by the upstanding teeth 10 and will be firmly held against sliding longitudinally

or laterally of the running board. The resistance offered by teeth constructed in the manner shown will firmly anchor the ice block, and it will be noted that the teeth 5 will engage themselves in the ice block at an angle thereto. This additionally serves to maintain the block against sliding. By having the teeth struck up from the body of metal itself and thereby causing the latter 10 to be cut entirely through, it is apparent that air may gain access to the under surface of the plate when the latter is not used in supporting an ice block, thereby enabling the water which may have accumulated beneath 15 the plate to quickly dry and to prevent rusting or decay of the running board as well as corrosion of the plate 6.

While the above is a description of the invention in its preferred embodiment, it is 20 to be understood that various changes in the construction and arrangement of parts may be resorted to, if desired, without departing from the spirit of the invention as defined by the claims.

Having thus fully described our invention, 25 we claim:—

1. An ice supporting device comprising a plate provided with a roughened surface

consisting of rows of teeth arranged in pairs, the teeth of each pair being formed of opposed segments of a circle struck up along a diametrical line to provide upstanding oppositely projecting teeth, the teeth of one or more of the rows being arranged at an angle to the teeth of another row or rows to provide ice engaging surfaces to prevent a cake of ice from sliding in any direction on the plate. 30 35

2. An ice supporting device comprising an oblong rectangular plate provided with a roughened surface consisting of longitudinal rows of teeth arranged in pairs, the pairs of teeth of the rows being disposed in staggered relation to each other, the teeth of each pair being formed of opposed segments of a circle 40 struck up along a diametrical line to provide upstanding oppositely projecting teeth, the teeth of one or more of the rows being arranged at an angle to the teeth of another row or rows to provide ice engaging surfaces to prevent a cake of ice from sliding longitudinally or transversely of the plate. 45 50

In testimony whereof we affix our signatures.

HENRY WELSCH.
MOSES R. BUCHANAN.
